R. H. & W. H. COON.

THRASHING MACHINE.

No. 10,251.

Reissued Dec. 5, 1882.

UNITED STATES PATENT OFFICE.

RILEY H. COON AND WILLIAM H. COON, OF ONEIDA LAKE, NEW YORK.

THRASHING-MACHINE.

SPECIFICATION forming part of Reissued Letters Patent No. 10,251, dated December 5, 1882.

Original No. 245,791, dated August 16, 1881. Application for reissue filed March 20, 1882.

To all whom it may concern:

Be it known that we, RILEY H. COON and WILLIAM H. COON, residing at Oneida Lake, Madison county, and State of New York, have 5 invented certain new and useful Improvements in Thrashing-Machines, of which the following is a description.

The purpose of our invention is to so appor- 10 tion and balance the vibrating parts of our machine as to counteract all strains upon the stationary parts, hold the machine steady, and reduce the driving-power required to a minimum by thus properly balancing the moving parts.

15 The construction is as follows, referring to the accompanying drawings, in which—

Figure 1 is a vertical longitudinal section through the center of the machine. Fig. 2 is a perspective view of the separator or straw-car- 20 rier and its movable connections.

Similar letters represent corresponding parts in both figures.

A represents the inclosing case or frame of the machine, of a common form.

25 B is a stout sill of the frame, sustaining the boxes or bearings of the shaft D, which has two sunk cranks, E, in it inside the frame and near its bearings. Upon one end of the shaft D, outside the frame, there is a pulley, F, affixed 30 and driven by a band from the motive power.

G is a shaft extending across the machine, with bearings in the side frame, located in rear of and above the shaft D. Shaft G has a sunk crank, H, at its center, and near each of its 35 bearings a triangular plate or lever, II, is affixed firmly, so as to turn with it. These plates II are vibrated by pitmen K, uniting their lower ends with the cranks E.

The separator or straw-carrier is made in 40 two parts or sections, L M. The front section L, is suspended at its front end from the frame, just below the rear end of the concave o, by rods or bangers N, and receives the straw and grain after passing the thrashing-cylinder P. 45 The rear end of section L is pivoted to the upper end of the levers II, by which it receives a peculiar vibratory motion, best suited to carry the straw and separate the grain therefrom by giving it an upward and rearward

throw. The grain drops down onto a grain-table, S, below section L. This table S is supported at its front end on the upper ends of links or rods T, which are pivoted to the frame at their lower ends, and its rear end is pivoted by wrist-pins J on levers I, just below and in front of the shaft G, as clearly shown in Fig. 1, which gives it a short upward and rearward throw that carries the grain, chaff, &c., back to the riddles U. Upon the rear edge of section L there is a series of fingers, Q, inclining 55 downward over section M of the straw-carrier, to guide the straw as it drops upon said section rearward. The section M has a movement opposite to that of section L, which is thereby counterbalanced, its front end being pivoted 60 to the levers I below shaft G. The rear end of this section M is suspended on links or hanger-rods R, pivoted to the frame above. This section has also inclined fingers at its rear end, where the straw is discharged from 65 the machine. There is a grain-table, W, below section M. This table W is supported on the upper ends of links or rods at both its ends, as clearly seen in the drawings, and receives a shaking movement from a pitman, Y, that 70 connects it with sunk crank H on shaft G, before named.

By dividing the straw-carrier and connecting its sections L M at the center with the vibrating plates I, while their outer ends are 75 supported by links attached to the frame, plates I receive the force of their counteracting movements, which are thereby neutralized, and the grain-carriers, being connected with the central shaft, G, and plates I, also serve 80 to counterbalance the vibrating parts, so as to prevent all shocks and strains upon the frame and driving-shaft D.

Having thus described our machine, we 85 claim—

1. In a thrashing-machine, the combi- 90 nation of straw-shakers L M, arranged in suc-
cession, levers I I, connecting the adjacent ends of
said shakers, pivoted supports for said levers
between said shakers, pitmen K, and crank-
shaft E, constructed and arranged substan- 95
tially as and for the purposes specified.

2. In a thrashing-machine, the combination

of the crank-shaft G, levers I I, the carrier-sections L M, and grain-table W, as and for the purposes specified.

3. The combination of the double-crank shaft 5 D, crank-shaft G, and triangular plates I I, separators L M, grain-conveyers S W, and pit-men or connecting-rods K K Y, all arranged and operating substantially as and for the purposes herein shown and specified.

In testimony whereof we have hereunto affixed to our signatures in presence of two witnesses.

RILEY H. COON,
WILLIAM H. COON.

Witnesses:

CHARLES L. HOBART,
JOHN E. STIMSON.
